(57) **CLAIM**

The ornamental design of a furniture cable grommet edge, as shown and described.

DESCRIPTION

FIG. 1 is a perspective view of a furniture cable grommet edge, showing our new design;

FIG. 2 is a front view thereof; and,

FIG. 3 is a top view thereof.

1 Claim, 1 Drawing Sheet

FIG. 1

FIG. 2

FIG. 3

UNITED STATES PATENT AND TRADEMARK OFFICE
CERTIFICATE OF CORRECTION

PATENT NO. : Des. 530,547 S
APPLICATION NO. : 29/221543
DATED : October 24, 2006
INVENTOR(S) : Jay M. Henriott et al.

Page 1 of 3

It is certified that error appears in the above-identified patent and that said Letters Patent is hereby corrected as shown below:

Title page should be deleted and substitute therefor the attached title page.

Inventors: Title page, item [75] should read -- Kevin [R.] T. Rauscher --

Drawings:

Replace Sheet 1 showing Figs. 1 through 3, with attached sheet showing Figs. 1 through 3 as shown on the attached page.

Signed and Sealed this

Fourth Day of March, 2008
